attorneys.

UNITED STATES PATENT OFFICE.

FRED G. HARTWELL, OF CHICAGO, ILLINOIS, ASSIGNOR TO ARTHUR C. JOHNSTON, OF CHICAGO, ILLINOIS.

STOP FOR BRIDGE TOWERS.

Application filed April 10, 1924. Serial No. 705,710.

To all whom it may concern:

Be it known that I, FRED G. HARTWELL, a citizen of the United States, residing at Chicago, in the county of Cook and State 5 of Illinois, have invented a certain new and useful Improvement in Stops for Bridge Towers, of which the following is a specification.

My invention relates to improvements in 10 stops for bridge towers and is adapted to provide a positive stopping and holding means which may be operated in conjunction with and in cooperation with the ordinary type of rail clamp used to hold the 15 bridge towers of traveling bridges in position. One object of my invention is to provide a positive attachment to the rail which will supplement the ordinary rail clamp. Another object is to provide a positive locking 20 means which will go into active operation only after an initial movement of the bridge. Another object is to provide means which may be manually interposed between the trucks and the rail to limit the movement 25 of the tower along the rail without interfering with the necessary slight adjusting movement. Other objects will appear from time to time in the specification and claims.

30 My invention is illustrated more or less diagrammatically in the accompanying drawings, wherein—

Figure 1 shows a side elevation of the parts of a tower with my invention in use; 35 Figure 2 is a side elevation on an enlarged scale of the rail engaging element;

Figure 3 is a section taken vertically and transversely through the structure of Figure 2.

40 Like parts are indicated by like characters throughout the specification and drawings.

A A¹ are supporting trucks from which rise the legs A² A³ of a bridge tower. These 45 trucks are carried by a plurality of rail engaging wheels A⁴, are tied together by the tie-beam A⁵ and are free to travel along the rail A⁶. Mounted on the tie-beam A⁵ are rail clamps A⁷ adapted to engage and 50 clamp the rail. These clamps may be automatic or controlled by the operator as the case may be.

B is a stop block adapted to rest on the top of the rail. It is provided at its center 55 on opposed sides of the rail with down-

wardly depending ears B¹ B¹. These ears are apertured at B² in line with holes B³ drilled in the web of the rail. B⁴ is a holding pin adapted to be thrust through the ears B² and the web to positively lock the 60 block in position on the rail. The stop block tapers downwardly toward either end from the center along a gradual radius of curvature and at its extreme end is narrowed down as indicated at B⁵. B⁶ B⁶ are bosses 65 on either side of the block and B⁷ is a hole drilled or cored through these bosses and the block. B⁸ is a link forged in the hole B⁷ and loosely contained therein. B⁹ is a flat broad cable spliced in the link B⁸ and 70 spliced on a pin B¹⁰ on the trucks A A¹.

In operation the blocks B are carried on the trucks when the bridge is being moved. As soon as it reaches the place where it is going to stop, these blocks are taken off, 75 placed on the rail, moved until the holes in the ears on the block are in line with the holes in the rail; the holding pins are then put in, the cable is always slack so that the bridge may be free to move slightly during 80 operation or for adjustment without interfering with the position of these blocks.

In the event that the bridge gets out of control of the operator or in the event that a windstorm or the like moves the bridge 85 against the normal holding of the clamps, movement will continue only far enough to tighten up the cable on the side opposite to the direction of movement, when movement will be stopped unless sufficient pressure is exerted to break the cable. These blocks are ordinarily so positioned that by the time the cable is under tension, the leading truck wheel will have reached the block on the side of the direction of movement and will tend to ride up the inclined surface. Thus the blocks have a double function, one serving as anchorage for the cable, the other serving as a stop to limit the forward movement by engagement directly with the wheel. It will be evident that while this arrangement of block and cable is particularly intended for use with traveling bridges, it might be used for any other purpose where it is desired to limit 100 the movement along the rail of a wheel supported element and it is also evident that the device might be used in connection with a single truck or there might be two of them in connection with each truck for the 105 110

bridge. It will be evident, therefore, that the showing I have made must be considered more or less diagrammatic.

I claim:

- 5 1. A removable anchor block adapted to engage a rail, for travelling members, comprising a body and wheels adapted to rest upon a track, said block having perforated ears depending downwardly from the sides 10 of said block in line with perforations in the track, a removable lock pin adapted to pass through said perforated ears and opposed perforations in the track to hold the block in place, and a flexible member attached to the block at one end and a travelling member at the other.
- 15 2. A removable anchor block adapted to engage a rail, for travelling members, comprising a body and wheels adapted to rest 20 upon a track, said block having perforated ears depending downwardly from the sides of said block in line with perforations in the track, said ears being spaced apart a distance substantially equal to the width 25 of the upper portion of the rail, a removable lock pin adapted to pass through said perforated ears and opposed perforations
- 30 in the track to hold the block in place, and a flexible member attached to the block at one end and a travelling member at the other.
- 35 3. A removable anchor block adapted to engage a rail, for travelling members, comprising a body and wheels adapted to rest upon a track, said block having perforated ears depending downwardly from the sides 40 of said block in line with perforations in the track, a removable lock pin adapted to pass through said perforated ears and opposed perforations in the track to hold the block in place, and a flexible member attached to the block at one end and a travelling member at the other, the block being 45 provided with an extension lying on the track and having upwardly inclined surfaces substantially tangent to the track at their lower extremities and curved upwardly toward the top of the block to provide a stop which may be engaged by the 50 bridge wheels.

Signed at Chicago, county of Cook and State of Illinois, this 18th day of March, 1924.

FRED G. HARTWELL.
